UNITED STATES PATENT OFFICE.

FREDERICK H. MILLER, OF WILKINSBURG, PENNSYLVANIA, ASSIGNOR TO WESTINGHOUSE ELECTRIC AND MANUFACTURING COMPANY, A CORPORATION OF PENNSYLVANIA.

GYRATORY FAN.

1,227,291.

Specification of Letters Patent. Patented May 22, 1917.

Application filed May 11, 1914. Serial No. 837,728.

To all whom it may concern:

Be it known that I, FREDERICK H. MILLER, a citizen of the United States, and a resident of Wilkinsburg, in the county of Allegheny and State of Pennsylvania, have invented a new and useful Improvement in Gyratory Fans, of which the following is a specification.

My invention relates to rotary electric fans, and it has particular reference to gyratory fans that are adapted to turn on an axis of rotation while simultaneously and automatically turning about an axis of revolution.

One object of my invention is to provide a gyratory fan having simple and effective mechanical means for effecting both the rotation and the revolution of the fan blades.

Another object of my invention is to provide a gyratory fan in which a plurality of sets of fan blades are driven by a single prime mover.

Another object of my invention is to provide a gyratory fan of compact and durable construction, the fan members of which may be readily adjusted to deliver air currents either horizontally or at any desired upward or downward inclination.

The single figure of the accompanying drawing is a vertical sectional view of a ceiling fan embodying my invention.

In designing rotary fans of the ceiling and column type, attempts have heretofore been made to substitute, for the usual paddle blades, a set of independently rotating fans, similar to the familiar desk and bracket fans, which rotate about an approximately horizontal axis and are also caused to revolve about a common vertical axis so as to force currents of air horizontally in all directions. The fans of this type, as heretofore designed, have been made up of two or more fan motors mounted on a rotatable support, and the rotation of the support has usually been effected by inclining the fan motors on their vertical axes and so generating a backward reaction or thrust, as the fans rotate, thereby causing the support to revolve. It is difficult, however, to obtain regular rotation of the support when the thrust of the fans is relied upon as the driving force, and it is impossible to rotate the support as slowly as is sometimes desirable. I have provided

a fan of the general type above described in which both the rotation of the fans and their revolution about their common axis are positively and mechanically effected, and in which a single motor drives all of the fans and also causes their support to rotate at a speed which can be varied within a wide range.

Referring now to the drawing, a plurality of sets of fan blades 1 are secured to the outer ends of a like number of horizontal shafts 2 that are supported in bearings in a hollow casing 3. The casing 3 consists of tubular arms 4, one of which surrounds each of the shafts 2, and a cylindrical casing 5 that is approximately perpendicular to the first-mentioned tubular arms.

I provide means for rotating the fans 1 and for simultaneously rotating the casing 3 about its vertical axis, the said means comprising, in the example shown in the drawing, a single motor having stationary field magnets 7 and a rotary armature 6. Coupled to the lower end of the armature shaft of the motor is a shaft 8 which rotates at the same speed as the armature shaft and in alignment therewith. The shaft 8 terminates in a bevel gear wheel 9 that meshes with similar bevel gear wheels 10, one of which is secured to the inner end of each of the shafts 2. It will be evident that the shaft 8 and the bevel gearing described will cause the fans 1 to rotate with the armature shaft of the motor, and at a speed depending upon the relative numbers of teeth in the gear wheels 9 and 10. It will also be apparent that other power transmitting gearing may be employed instead of the bevel gear wheels 9 and 10 for driving the shafts 2. For example, the shaft 8 may terminate in a friction disk 95 coöoperating with friction wheels that take the place of the bevel gear wheels 10 on the shafts 2.

The casing 3, which supports the fans, must be caused to rotate much more slowly than the armature shaft of the motor, and I therefore provide speed-reducing gearing between the armature shaft and the casing 3. In the embodiment of my invention shown in the drawing, such gearing comprises a small pinion 11 on the shaft 8 that meshes with a gear wheel 12, of much larger

diameter than the pinion 11. The gear wheel 12 is mounted on a stub shaft 13, on which is also mounted a small pinion 14 that meshes with a gear wheel 15 secured to the upper end of the cylindrical portion 5 of the casing 3. By the train of gearing just described, the rapid rotation of the armature shaft is converted into slow rotation of the casing 3. The driving motor is enclosed within a casing 16 of any desired ornamental form, and the casing 16 is provided with means for rotatably supporting the upper end of the cylindrical arm 5 of the casing 3. As shown on the drawing, such supporting means comprises bearing balls 17 disposed in a circular ball-race 18 and supporting a bearing ring 19 that may either be formed integral with the gear wheel 15, as shown, or be secured, in any other suitable manner, to the casing 3.

If it is desired to combine my fan structure with a stationary electrolier, the armature shaft of the driving motor and the shaft 8 may be hollow, and a stationary rod 20 may extend through both of these hollow shafts to a point below the bevel gear wheels 9 and 10 and may support, at its lower end, electric lamps 21 of any suitable form and arrangement. The rod 20 may be composed of insulated conductors for supplying current to the lamps of the electrolier and also for bringing the terminals of the motor circuit within convenient reach for starting and stopping the motor. One or more switches 22 may be fixed to the lower end of the rod 20 for controlling the excitation and speed of the motor and the illumination of the lamps.

I prefer to secure the fans 1 to the outer ends of the shafts 2 in such a manner as to permit their vertical inclination to be readily varied, so that they may be caused to deliver air either horizontally, downwardly, or upwardly. In the structure shown in the drawing, this adjustable connection comprises a short length 23 of flexible shafting, by means of which each fan is secured to its shaft 2. The tubular arms 4 of the casing 3 are provided with joints 24, which permit the outer ends of the arms 4 to adapt

themselves to the inclination of the short flexible shafts 23.

While I have described my invention as applied to a fan of the ceiling type, it is obvious that it is equally applicable to fans 55 of the column type, and, under some circumstances, it may also be employed in fans in which the support rotates in other than a horizontal plane. Other changes and modifications may readily be made in the 60 structure shown and described without departing from the spirit of my invention, and I therefore desire that only such limitations shall be imposed as are indicated in the appended claims. 65

I claim as my invention:

1. A gyratory fan comprising a plurality of sets of fan blades, an electric motor provided with an extended armature shaft operatively connected to said fan blades, reduction gearing connected to said motor shaft, a casing inclosing said motor and said gearing, a cylindrical casing axially alined with said armature shaft and comprising arms for supporting said fan blades, a gear member carried by said cylindrical casing and meshing with said reduction gearing and means interposed between said gear member and the bottom of said motor casing for rotatably supporting said cylindrical casing. 75

2. A gyratory mechanism for fans comprising a motor, reduction gearing connected to the shaft of said motor, a casing inclosing said motor and said gearing, a cylindrical casing axially alined with said motor shaft, a gear member carried by said casing and meshing with said reduction gearing and a plurality of balls circumferentially arranged between said gear member and said motor casing for rotatably supporting said cylindrical casing. 85

In testimony whereof, I have hereunto subscribed my name this 28th day of April 1914.

FREDERICK H. MILLER.
